UNITED STATES PATENT OFFICE.

ERNEST A. HUSS, OF HASWELL, COLORADO.

TRAIN-ORDER CRANE

1,069,428.

Specification of Letters Patent. Patented Aug. 5, 1913.

Application filed April 2, 1913. Serial No. 758,410.

To all whom it may concern:

Be it known that I, ERNEST A. HUSS, a citizen of the United States, residing at Haswell, in the county of Kiowa and State of Colorado, have invented new and useful Improvements in Train-Order Cranes, of which the following is a specification.

The invention relates to a despatch receiving and delivery device, and more particularly to the class of train order cranes for use in railway stations and the like.

The primary object of the invention is the provision of a device of this character wherein despatches or train orders may be readily and quickly exchanged, received or delivered to a moving train or station without necessitating the stopping or reducing of the speed of travel of the said train.

Another object of the invention is the provision of a device of this character wherein orders or despatches can be delivered to both or either end of a railway train while in motion without reducing its speed of travel, the possibility of missing the despatches or orders being obviated, this preventing delays in traffic and also which avoids accidents to the station operator or train crew.

A further object of the invention is the provision of a device of this character which will work perfectly in rainy or freezing weather, there being no slides, fasteners or complicated working parts to get out of order.

A still further object of the invention is the provision of a device of this character which is simple in construction, reliable and efficient in operation, and inexpensive in manufacture.

With these and other objects in view, the invention consists in the construction, combination and arrangement of parts as will be hereinafter fully described, illustrated in the accompanying drawings, and pointed out in the claims hereunto appended.

In the drawings:—Figure 1 is a fragmentary end elevation of a locomotive cab showing the crane constructed in accordance with the invention in relative position thereto.

Fig. 2 is a similar view showing the crane shifted when not in use. Fig. 3 is a fragmentary vertical sectional view through one of the arms of the crane, showing the mounting of the permanent magnet therein. Fig.

4 is a sectional view on the line 4—4 of Fig.

1. Fig. 5 is a perspective view of one of the despatch or order carriers or holders.

Similar reference characters indicate corresponding parts throughout the several views in the drawings.

60

Referring to the drawings by numerals, the device comprises a base or bed frame 10 which is preferably constructed from beams or sills suitably mounted in the ground or foundation adjacent to one side of a railway track 11, and are connected together in any suitable manner. Superposed above the base or bed 10 is a platform 12 which is supported upon legs 13, the same being secured thereto and also fastened to the said bed in any desirable manner. Formed centrally in the bed 10 is a bearing 14, while passed through the platform 12 is a rotatable standard or crane 15, the same being formed with a lower journal end 16 which loosely engages 75 in the bearing 14, the said standard or crane 15 being rounded at 17 at the point of intersection thereof with the platform 12 so that the said standard or crane can be readily rotated, the remaining portion of the 80 standard or crane 14 being square in cross section, although it may be of any other desirable shape.

Integrally formed with the crane or standard 15 or secured therein are a plurality of 85 pairs of arms 18, 18' and 19 respectively, which extend outwardly at right angles to the said standard or crane and are formed at their outer ends with sockets 20 in which are adjustably inserted permanent magnets 90 21, the same being held in adjusted position through the medium of set screws 22 which are threaded in one side of the arms, the purpose of the permanent magnets 21 being hereinafter more fully described.

95 Fixed to the standard or crane 15 above the platform 12 is an extension 23 to which is pivoted at 24 a swinging handle 25, the same being adapted for engagement in notches 26 formed in the edges of the platform 12, the said handle being designed to 100 permit the turning of the standard or crane 15 and also for locking it in shifted position to hold the same set for use or disuse.

105 The standard or crane 15 is shifted so that the arms 18 and 19 will project at right angles to the longitudinal extent of the track and when not in use the said crane or standard will be thrown so that the arms will 110 project parallel with the track.

Adapted to be caught and held by the permanent magnets 21 in the arms 18 and 19 are despatch or train order carriers, each comprising a bar 27 to which is connected 5 a looped handle or bail 28, the same being fixed to the bar in any suitable manner. Mounted on the outer face of the bar is a metallic plate 29 which is designed to be attracted by the magnets 21 when the bar is 10 brought into close relation thereto so that the carrier will be caught and held by the magnets 21, one end of the bar being formed with a handle 30 which permits the manual manipulation thereof for the placing of the 15 carrier upon the magnets 21 on the lower pair of arms 19 by a station operator, or when the carrier is removed from the magnets 21 of the upper pair of arms 18 after being placed by the station operator or other 20 member while the train is traveling upon the track.

Suitably fixed to each bar 27 of the carrier is a spring clip 31 which is adapted to engage despatches or train orders for the holding 25 of the same in the carrier. Fixed in the standard or crane 15 at an intermediate point between the arms 18 and 19 thereon is a hook 32 which is adapted to support a lantern whereby the despatch or train order carriers 30 can be visible both to the train crew or the station operator, at night.

From the foregoing it is thought that the construction and manner of operation of the device will be clearly understood, and therefore 35 a more extended explanation has been omitted.

What is claimed is:—

1. A device of the class described comprising a standard adapted to be located adjacent to a track, arms projecting outwardly from the said standard, permanent magnets mounted in the arms and projecting therefrom, and despatch carriers adapted to be caught by the magnets when brought in the 40 fields thereof.
2. A device of the class described comprising a standard adapted to be located adjacent to a track, arms projecting outwardly from the said standard, permanent magnets 45 mounted in the arms and projecting therefrom, despatch carriers adapted to be caught by the magnets when brought in the fields thereof, and means for securing the magnets in the said arms.

3. A device of the class described comprising a standard adapted to be located adjacent to a track, arms projecting outwardly from the said standard, permanent magnets mounted in the arms and projecting therefrom, despatch carriers adapted to be caught by the magnets when brought in the fields thereof, means for securing the magnets in the said arms, and a platform rotatably supporting the said standard.

4. A device of the class described comprising a standard adapted to be located adjacent to a track, arms projecting outwardly from the said standard, permanent magnets mounted in the arms and projecting therefrom, despatch carriers adapted to be caught by the magnets when brought in the fields thereof, means for securing the magnets in the said arms, a platform rotatably supporting the said standard, and looped handles formed on the said carriers.

5. A device of the class described comprising a standard adapted to be located adjacent to a track, arms projecting outwardly from the said standard, permanent magnets mounted in the arms and projecting therefrom, despatch carriers adapted to be caught by the magnets when brought in the fields thereof, means for securing the magnets in the said arms, a platform rotatably supporting the said standard, looped handles formed on the said carriers, and means for locking the standard in adjusted position.

6. A device of the class described comprising a standard adapted to be located adjacent to a track, arms projecting outwardly from the said standard, permanent magnets mounted in the arms and projecting therefrom, despatch carriers adapted to be caught by the magnets when caught in the fields thereof, means for securing the magnets in the said arms, a platform rotatably supporting the said standard, looped handles formed on the said carriers, means for locking the standard in adjusted position, and a lantern support carried by said standard.

In testimony whereof I affix my signature in presence of two witnesses.

ERNEST A. HUSS.
